OZONIZER WITH MOVABLE COVER

Sandra Lucchi, % Misitano, Via Padova 217,
Milan, ItalyFiled Jan. 3, 1969, Ser. No. 15,192
Claims priority, application Italy Dec. 21, 1968

Term of patent 14 years

Int. Cl. D23—04

U.S. Cl. D23—150

FIG. 3
FIG. 4FIG. 1 is a side view of the book shaped ozonizer with the cover in an upright position;

FIG. 2 is a side view as FIG. 1 but of the opposite side;

FIG. 3 is a front view thereof as seen from the right of FIG. 1;

FIG. 4 is a top plan view thereof.

I claim:

The ornamental design for an ozonizer with movable cover, as shown and described.
